UNITED STATES PATENT OFFICE

SIDNEY LEAR, OF GERMANTOWN, PENNSYLVANIA

EASEL SUPPORT

Application filed July 2, 1929. Serial No. 375,562.

The object of my invention is to provide a book cover which will protect the binding of a book and which will also form an easel or rest for the book, so that the book can be held in the open position while being read.

My invention also relates to means for holding the covers of a book firmly to the easel, as well as to means which will allow for the fitting of books of different sizes to the easel.

A further object of the invention is to provide an easel support for a book or other article, which will be capable of being folded when the easel section is in the closed position, but when it is extended to support the body portion, then it will lock the body portion in the open position.

In the accompanying drawings:

Fig. 1 is a perspective view of the easel, showing it in the open position and with the book omitted;

Fig. 2 is a view similar to Fig. 1, showing the book secured to the easel book cover and in reading position;

Fig. 3 is a side view of the easel with the book in position;

Fig. 4 is a plan view of the cover with the easel support folded in a flat condition;

Fig. 5 is a rear view of the easel book cover in a flat condition;

Fig. 6 is a perspective view showing the easel book cover folded, the book being omitted;

Fig. 7 is a detailed fragmentary view showing a portion of the cover folded over a book;

Fig. 8 is a sectional view on the line 8—8, Fig. 4; and

Fig. 9 is a sectional view on the line 9—9, Fig. 4.

Referring to the drawings, 1 is the book cover, which may be made of cardboard or other suitable material and which may be covered with paper or leather as desired. The book cover is made of two side sections 2—2 and two narrow sections 3—3 on each side of the centre, and these sections are connected together by thin hinge strips 4, so that the book cover can be folded in either

the position shown in Fig. 6 or can be folded over a book as in Fig. 7.

In order to secure a book to the easel, retaining flaps 5 are hinged at 6 to the upper edge of the easel, and short retaining flaps 7 are hinged at 8 to the lower portion of the easel and these two can be secured together by any suitable fastenings 9. In the present instance, an extension on the lower end of each flap 5 is secured by a snap-fastener to the flap 7.

The easel is made preferably of such height that it can retain books of different heights as shown in Fig. 2, and the flaps 5 and 7 fit between the leaves of the book and the cover and are clamped thereto, firmly retaining the book to the easel and allowing the leaves to be freely turned.

In many instances it is desirable to support a book on an easel so that it can be conveniently read, particularly in a sick room or on a table adjacent to an easy chair, and in order to provide such a support I combine with the book cover an easel, the body 1 of the book cover forming a support for a book, and hinged to this body at 10 is an easel section 11 which can be moved to the supporting position as in Fig. 1, the outward movement of the easel support being controlled by strips of tape 12 which are secured to the back of the body portion 1 and the easel support as shown.

The narrow strips 3 are continued through the support 11 as clearly shown in Figs. 1, 4 and 5, and the hinge members 4 are also continued, so that when the support is folded the cover can be closed as in Fig. 6. By making the easel in this manner, it can be readily opened and closed on its hinges, but the moment the support is opened to support a book as in Fig. 1, the hinge portions of the support are out of line with those of the cover and form a rigid lock, which will prevent the book cover being folded when the support is in its open position. This is very essential, as it is necessary to have the book cover rigid when the cover is in use.

In order to insure the opening of the supporting section when the easel book cover is opened, I provide a spring of any suitable

shape, which is under tension when the cover is closed, and when the cover is opened it will immediately force the supporting section away from the body of the cover and retain it in the open position. The spring may be a flat spring as shown in Fig. 4, or it may be a coil spring, one end being attached to the body portion and the other end attached to the support.

10 While the main object of my invention is to provide a support which will act as a cover for a book to which it is attached, it will be understood that in some instances the support may be used for holding or carrying other objects, the body portion being capable of being folded when flat, when the easel section is in the closed position, but when the easel section is extended, it will not only support the body portion but will lock the sections of 20 the body in the open position.

I claim:—

1. The combination in an easel support, of a body portion having a center longitudinal hinge, and an easel section transversely 25 hinged to the body portion on a line crossing the longitudinal hinge line of the body portion, so that when the easel section is extended it will lock the body portion in the open position.

30 2. The combination in an easel support, of a body portion open at the center and having longitudinal hinged sections; and an easel section also having hinged sections in line with the body portion when the body portion 35 is closed, said easel section being transversely hinged to the body portion on a line crossing the hinged line of the body portion, the easel section locking the hinged sections of the body when in the open position.

40 3. The combination in an easel support, of a body portion having side sections; two narrow longitudinal sections, one on each side of the center, said sections being connected together by a hinged strip and connected to the 45 side sections by hinges; and an easel section transversely hinged to the body portion on a line crossing the hinged line of the main portion, said easel section having hinged sections corresponding with those of the body portion, said hinged section locking the body portion when said section is extended and the body portion is in the open position.

50 4. The combination in an easel support, of a body portion having an opening at the center; a transversely hinged easel section located within the opening of the body portion, said body portion and the hinged easel section each having a longitudinal hinge, the hinge of the easel section being in line with 55 the hinge of the body portion when closed, said longitudinal hinge being on a line crossing the hinge line of the hinged section, the hinged section being locked in position when the body portion is folded.
